DESIGN FOR A LUGGAGE LOCK OR SIMILAR ARTICLE

David Levine, New York, N. Y.

Application February 5, 1942, Serial No. 105,644

Term of patent 14 years

To all whom it may concern:

Be it known that David Levine, a citizen of the United States and resident of Manhattan, in the county of New York and State of New York, has invented a new, original, and ornamental Design for a Luggage Lock or Similar Article, of which the following is a specification, reference being had to the accompanying drawing forming part thereof, in which the figure is a perspective view

of a luggage lock or a similar article showing my new design. The dominant features of my design reside in the portions shown in full lines. The rear of the lock is conventional.

I claim:

The ornamental design for a luggage lock or similar article, substantially as shown and described.

DAVID LEVINE.
